UNITED STATES PATENT OFFICE.

EMORY P. WALKER, OF BELCHERTOWN, MASSACHUSETTS.

IMPROVEMENT IN BUTTER-WORKER.

Specification forming part of Letters Patent No. 77,135, dated April 21, 1868; reissue No. 3,943, dated April 15, 1870; application filed April 7, 1870.

To all whom it may concern:

Be it known that I, EMORY P. WALKER, of Belchertown, in the county of Hampshire, and in the State of Massachusetts, have invented certain new and useful Improvements in Butter-Workers; and I do hereby declare that the following is a full, clear, and exact description thereof, reference being had to the accompanying drawings, and the letters of reference marked thereon:

In the annexed drawings, making a part of this specification, A represents the bottom of a rectangular box or frame having a hole, x, through it near the front end; B B, the sides of the same, provided with slots a a, extending nearly the whole length of them; C, one end of the frame, the top being cut away as low as the lower sides of the slots a a, and D D the front end pieces, placed diagonally so as to form an apex at their intersection, in the middle of the bottom A, and just in front of the hole x. The whole is supported by suitable legs c c c c, the two in front sufficiently shorter than the others to give the desired pitch or inclination to the frame. d d represent arms or holders framed together by the handle c' at one end, and the guide-bar g at the other, which extends through the

sides B B, and slides backward and forward in the slots a a. A roller h is adjusted into arms d d, and works on the face of the bottom A to press and thoroughly work buttermilk or other liquids out of butter, or mix different grades or colors of butter, making the mixture a homogeneous mass, and of uniform color. The pieces D D are designed to hold the butter from being pushed over the end of the bottom A, and to conduct the water or other liquid to the hole x. N represents a paddle to handle the butter with, so that it is unnecessary to touch the butter at all with the hands.

What I claim as my invention, and desire to secure by Letters Patent, is—

The arms d d constructed with the guide-bar g, sliding in the slots a a, in combination with the adjustable roller h, bottom A, flanges D D, placed at the mouth or front end A, and hole x, when all the parts are constructed and arranged with reference to a butter-worker, and operated substantially as described.

EMORY P. WALKER.
